LAWN MOWER GRASS CATCHER CHUTE

Victor Leader, Minneapolis, Minn.
(21324 Lake George Drive NW, Cedar, Minn. 55011)

Filed May 1, 1975, Ser. No. 573,454

Term of patent 14 years

Int. Cl. D15—03

U.S. Cl. D40—1 A

FIG. 1 is a right side elevational view of a lawn mower grass catcher chute showing my new design; the left side being a mirror image of FIG. 1;

FIG. 2 is a rear elevational view of FIG. 1;

FIG. 3 is a front elevational view of FIG. 1;

FIG. 4 is a top plan view of FIG. 1; and

FIG. 5 is a bottom plan view of FIG. 1.

I claim:

The ornamental design for a lawn mower grass catcher chute, substantially as shown.
